UNITED STATES PATENT OFFICE.

ALBERT BALL, OF CLAREMONT, NEW HAMPSHIRE, ASSIGNOR TO THE SULLIVAN MACHINE COMPANY, OF SAME PLACE.

CORE-BREAKER FOR ANNULAR ROCK-DRILLS.

SPECIFICATION forming part of Letters Patent No. 366,914, dated July 19, 1887.

Application filed November 13, 1886. Serial No. 218,776. (No model.)

To all whom it may concern:

Be it known that I, ALBERT BALL, of Claremont, in the county of Sullivan and State of New Hampshire, have invented a new and Improved Core-Breaker for Annular Rock-Drills; and I do hereby declare that the following is a full and exact description of the same, reference being had to the accompanying drawings, and to the letters of reference marked thereon.

10 My invention relates to core breakers and lifters for prospecting or annular rock-boring drills; and my improvements are intended to break and secure the most perfect core automatically and operate on the principle of 15 keeping the core-breaking wedges away from the core until it is desired to break and remove the same.

My several devices for which Letters Patent numbered severally 315,887, 315,888, and 20 315,889 have been granted upon application made by me and the device for which I intend to make application simultaneously herewith are on the same principle, and I hereby disclaim in this application all that is shown in 25 said Letters Patent and what is claimed in said other application to be filed herewith. In the patents and application aforesaid the wedges are brought into action by the use of a valve or equivalent mechanism operated by the engineer from without, while in this invention the action is automatic.

When commencing to drill, the wedges are held up and away from the core, either by means of a light spring-latch or by means of a 35 temporary core made of rubber or some other suitable material, until the drilled core enters the wedge-driver, when the core itself serves to hold up the same, all as will be more fully hereinafter described and claimed.

40 For the better comprehension of my invention reference should be had to the accompanying drawings, wherein like letters refer to corresponding parts, and in which—

Figure 1 is a longitudinal section of a core-lifter shell and drill-head embodying my improvements. Fig. 2 is an end view of a diamond-armed bit, showing a rubber substitute for the core. Fig. 3 is a top view of the wedge-driver. Fig. 4 is a side elevation, partly in 50 section, of the wedge-driver with one wedge at-

tached thereto. Fig. 5 is a central vertical section of the core lifter shell and cutting-bit. Fig. 6 is a side elevation of the jacket inclosing the wedge-driver, and showing the spring-latch attached thereto. Fig. 7 is a top view of the diamond-armed bit, showing the inclined slots for the wedges. Fig. 8 is an end view of the jacket. Fig. 9 is a longitudinal section of the core-lifter shell, including the core-barrel and the jacket.

55 My device consists, essentially, of four parts: First, of a cylindrical piece which I call the "wedge-driver," E and D, Figs. 1, 3, 4, 5, and 6, and which, when it is reached by the core, is designed to remain stationary therewith. For part of its length this wedge-driver is constructed of a spring, D, designed to clasp the core as the drill descends. The upper part, E, is heavier and without spring, and has a serrated top and one or two grooves 60 around the outside, as will be more fully hereinafter described.

Second, of a series of independent wedges, F, Figs. 1, 4, and 5, suspended by means of their bent upper ends from one of the grooves 65 K, Figs. 4, 5, and 6, on the outside of the wedge-driver, whereby they have free movement around the wedge-driver when the latter is stationary. The wedges are preferably made stiff, with neither an outward nor an inward spring, and pass down through slots L, Fig. 9, of a "jacket," G, into inclined slots 70 K' of the cutting-head, so as to have only longitudinal movement relative to the drill-rod and cutting-head.

80 Third, of a jacket or frame, G, Figs. 1, 5, 6, 8, and 9, in which the wedge-driver is placed, and which has slots to receive the wedges. It is preferably made the length of the unthreaded part of what is technically known as the 85 "shell," (or core-lifter shell A, Figs. 1, 5, and 9.) This shell is a short length of tubing between the end of the "core-barrel" H, Fig. 9, and the diamond-armed bit B, Figs. 1, 2, 3, 7, and 9, made with a larger inside diameter 90 than the same, so as to leave shoulders (see Figs. 1, 5, and 9) on the inside, both at its top and bottom. This jacket G turns with the drill-rod, and is held up together with the wedge-driver, by the wedges themselves, and 95 100

is made longer than the wedge-driver to allow for the proper working of the wedges in breaking the core when it is desired to "pull up."

Fourth, of devices to keep the wedge-driver up and to keep the wedges from contact with the core until the core shall reach the aforesaid spring D in the wedge-driver and be grasped by it. These devices have to be automatic, and either of the following can be used to make them so: A temporary core made of rubber or other suitable material so constructed as to leave spaces for the free passage of the water, and which, when placed inside the shell so as to rest on the top of the diamond-armed bit, is grasped by the wedge-driver spring D and holds up the wedge-driver. As the drill advances, the core forces up this temporary core and assumes its function. It is obvious that a short piece of "core" previously taken out can be used instead of the rubber or other substitute. Or a latch consisting of a light spring, I, Figs. 5 and 6, is fastened at one end by a rivet, M, in one of the exterior recesses of the jacket, and its free end is forced into a groove, J, Figs. 4 and 5, cut under and around the top end of the wedge-driver and provided with an opening, N. This spring is latched by pressing it in the said groove through the opening N, and by slightly turning the jacket on the wedge-driver the spring is carried farther around in the groove, and the wedge-driver and the jacket G are thus temporarily locked together and prevented from separating longitudinally. This spring, when so latched, keeps the wedge-driver and wedges up and back from the core.

Before proceeding to drill, the wedge-driver and its jacket are locked together, as hereinbefore described. When the core is long enough, it is grasped by the spring of the wedge-driver, and this prevents the latter from turning with the drill; but the wedges and the jacket continue to revolve with the drill around the wedge-driver until the spring I (which is attached to this jacket) is brought opposite the opening N in the groove J of the wedge-driver, when said spring, by reason of its outward pressure, frees itself from engagement with the latter. The function of this spring then ceases, and the wedges and the wedge-driver are free to act, so that when the drill-rod is pulled up the wedges are made to firmly grasp the core.

The wedge-driver has preferably a serrated top, (see Figs. 3, 4, 5, and 6,) to allow the free passage of the water, and the jacket is also provided with spaces for this purpose.

The wedges and the grooves in the jacket L, Fig. 9, which are occupied by the arms of the same, and the slots in the bit L', Figs. 7 and 9, in which the said wedges move, are so made that as the wedges are driven down they are at the

same time forced inward and against the core, and when elevated they are held back from the same. This is accomplished by varying the depth of the grooves and the thickness of the wedges and wedge-arms.

The wedges proper are at the end of short arms, which at the other (the top) end have projections which move in the recess K in the top of the wedge-driver.

In matters of detail other equivalent devices could be substituted for some I have shown in my drawings and description, and to which therefore I do not wish to be strictly confined. It will also be understood that this temporary core is equally serviceable and valuable in other forms of core-lifters which are provided with a device for grasping the core.

Having thus described my invention, what I claim as new, and wish to secure by Letters Patent, is—

1. A core-breaking tool the breaking-wedges whereof are automatically kept away from contact with the core during the process of drilling by means of a temporary core or latch, but are brought into breaking contact therewith by the core itself when the drill-rod is pulled up, substantially as described.

2. In combination with a core-barrel and an annular drill-head, the breaking-wedges F and the wedge-driver around which the wedges are free to revolve, and which is adapted to grasp the core, substantially as and for the purpose described.

3. In combination with a core-barrel, an intermediate shell, A, a wedge-driver, wedges free to act around the same, a jacket or frame provided with grooves, and an annular drill-head, also provided with grooves, substantially as and for the purposes described.

4. In combination with an annular drill-head and shell, a wedge-driver carrying wedges free to revolve around the same and a temporary core, C, substantially as and for the purpose described.

5. In combination with a core-barrel, an annular drill-head, and an intermediate shell, a wedge-driver, wedges free to revolve around said driver, a jacket or frame within which the wedge-driver works, and a spring-latch, I, substantially as and for the purpose described.

6. The combination, with an annular drill-head and shell and a core-lifting device provided with spring-clasps for holding the core, of a temporary core, substantially as and for the purposes set forth.

In testimony whereof I affix my signature in presence of two witnesses.

ALBERT BALL.
